UNITED STATES PATENT OFFICE.

DAVID H. LENTZ, OF JOLIET, ILLINOIS, ASSIGNOR TO THE MCKENNA
STEEL WORKING COMPANY, OF MILWAUKEE, WISCONSIN.

SAW-TABLE.

SPECIFICATION forming part of Letters Patent No. 621,106, dated March 14, 1899.

Application filed November 22, 1897. Serial No. 659,480. (No model.)

To all whom it may concern:

Be it known that I, DAVID H. LENTZ, a citizen of the United States, residing at Joliet, in the county of Will and State of Illinois, have 5 invented a certain new and useful Improvement in Saw-Tables, (Case No. 5,) of which the following is a full, clear, concise, and exact description, reference being had to the accompanying drawings, forming a part of this 10 specification.

My invention relates to a saw-table, and more particularly to a saw-table for a rail-mill, upon which saw-table a heated rail from the finishing-rolls is adapted to be sawed to 15 standard length.

The saw-table of my invention was designed to be used in connection with a rolling-mill for rerolling or renewing old steel rails, but its use is not limited to such application. As 20 the rail leaves the finishing-rolls it is very liable to be warped and twisted while cooling, the flange of the rail being comparatively thin, cooling more quickly than the head, and thereby causing this distortion. Twisting is 25 also frequently caused by the very action of the finishing-rolls themselves.

While it is usual to straighten rails after they become cold, it has been found very difficult and in some cases almost impossible to 30 straighten a rail which has twisted, especially as this twisting is frequently of different degrees in different parts of the rail, it sometimes happening that a double twist will be found. While a cold-straightening process 35 will bring the rail into correct alinement, it is usually necessary to provide special machinery for taking the twist out of the rail while cold, and it frequently happens that it cannot be taken out at all and the rail must be 40 rerolled. Such twisting is frequently manifested as the rail leaves the finishing-rolls, and it is the object of my invention to provide means for removing this twist while the rail is still sufficiently hot to yield easily to 45 straightening mechanism.

In accordance with my invention a number of clamps are arranged at intervals along the saw-table, forming a row in the line of the rail and at an angle with the plane of the 50 saw, said clamps having opposing members,

which are provided with flat unyielding engaging surfaces. These flat unyielding opposing surfaces engage the flat surfaces of the top and bottom of the rail as it lies upon the saw-table, and besides holding the rail firmly 55 while its ends are being sawed off are adapted to straighten the rail as it lies upon the saw-table in a heated condition and to remove any twist that may have formed therein. The clamps are preferably arranged in two sets, 60 working at right angles to one another, one set serving to remove distortion in a vertical plane, for instance, while the second set removes distortion at right angles to the plane of operation of said first set—as, for instance, 65 in a horizontal plane. The rail is thus effectually straightened and the twist removed therefrom. This straightening upon the saw-table cannot of course do away entirely with the necessity of cold-straightening, but it 70 greatly lessens the labor of the latter process and the twist is almost entirely removed.

I will describe the details of construction of a machine embodying one form of my invention in connection with the accompanying 75 drawings, in which—

Figure 1 is a plan view of the saw-table. Fig. 2 is an end view thereof, partly in section. Fig. 3 is an elevation of one end of the saw-table. 80

Similar letters of reference are used to designate similar parts in all the figures.

The framework of the table *a* is provided with a series of driven rollers *a'*, which are adapted to receive, support, and convey the 85 rail along said table. These rollers are adapted to be driven positively by a steam-engine *b* in a well-known manner. At either end of the framework and constituting continuations of the table are provided supporting- 90 frames *e e'*, upon which the saws *f f'* are mounted. The saws *f f'* are rotatably mounted in what are commonly known as "saw-slides" *g g'*, said saw-slides being movable to and fro along the frames *e e'*, respectively. 95 This movement is preferably effected by means of a steam-cataract *h*, and since this construction is so well known in the art I do not consider it necessary to further describe it. 100

Upon the supporting-frame e is provided a guide i , which forms the stationary member of a clamp, the movable member whereof consists of a clamping-bar k , which is adapted to slide to and fro along the top of the supporting-frame. Means for causing this movement will be presently described. In like manner the supporting-frame e' is provided with a clamp, consisting of a stationary member i' and a movable member or clamping-bar k' . Additional clamps are provided at intervals along the table a in the spaces between the rollers a' , forming a row in the line of the rail and at an angle with the plane of the saw, said clamps consisting of stationary members l and movable members m . The clamping-bar k is connected by arms o , pivoted thereto with bell-crank levers p , said levers forming toggle-joints. The outer ends of said bell-crank levers are connected with an arm q , which is pivoted at its other end to a rocking lever q' , pivoted at q^2 . The other end of said rocking lever is connected with an arm r , which extends to the supporting-frame e' and is there connected with the elbows of toggle-joints o' , which operate the clamping-bar k' . Toggle-joints m' are provided in connection with the clamping-bars m at other points along the table a , and the elbows of said toggle-joints are pivoted to the arm r . The rocking lever q' is provided with a right-angled extension q^3 , to the end of which is pivoted a connecting-arm q^4 , the other end of said connecting-arm being pivoted to the cross-head of a steam-cataract s . It will be seen that when the steam-cataract acts to retract its cross-head the lever q' will be rocked about its pivot q^2 , thus forcing the clamping-bar k toward the stationary guide i through the medium of arms o , bell-cranks k , and connecting-arm q . Simultaneously the clamping-bar k' upon the supporting-frame e' will be forced toward the stationary guide i' through the agency of the toggle-joints o' , connected to the arm r , the other clamps $m m$ upon the table a being likewise simultaneously caused to approach their stationary members l through the agency of the toggle-joints m' , connected to the arm r . If a rail lies between this series of clamps thus described, it will be seen that upon actuating the steam-cataract s the rail will be engaged by these clamps and straightened thereby in a horizontal plane, as well as being clamped securely in position upon the saw-table.

Since the clamps have flat and unyielding engaging surfaces the rail, besides being straightened, will have most of the twist removed. These rigid clamps will not bend the rail sharply or bite into the same, since the rail is not so hot as to be very soft, and the rigid flat surfaces of the clamps will merely bend those portions which are out of true into the proper position.

As is shown most clearly in Figs. 2 and 3, I provide a vertically-moving clamping-bar t ,

which is adapted to slide up and down in a plane at right angles with the movement of the clamping-bar k and is supported and guided in an upright extension of the guide i , which is provided upon said supporting-frame e . Arms $v v$ are pivoted to said bar t , forming toggle-joints with rocking levers w , pivoted to the extension of the guide i . Said rocking levers are connected with a rocking lever v' to a right-angled extension v^2 , whereof is connected an operating-arm which may be actuated by lever mechanism v^3 , connected with a right-angled extension q^3 of the rocking lever q' , so that upon actuation of the first-described set of clamps the vertically-moving clamping-bar t will simultaneously be caused to descend upon the rail, which may lie upon the saw-table. The supporting-frame e' is likewise provided with a vertically-moving clamping-bar t' , said clamping-bar being actuated by toggle-joints connected by an arm x with the rocking lever v' , so that the clamping-bar t will be forced downward to engage the rail simultaneously with the clamping-bar t .

I have found that it is unnecessary in most cases to provide vertically-moving clamps at other points along the saw-table—as, for instance, in connection with the horizontal clamps m ; but this may be done, if desired.

I preferably adjust the vertically-moving clamps $t t'$ so that they may engage the rail upon the saw-table slightly in advance of the horizontally-moving clamping-bars $k k'$.

Upon referring to Fig. 1, it will be seen that as a rail is received upon the saw-table the attendant may actuate the steam-cataract s , whereupon the system of clamps upon the saw-table will be caused to engage the rail at different points in the manner already described, and since these clamps consist of two sets, one set operating horizontally and another set operating vertically, the rail will be effectively straightened, and any twist which may have been present therein will be removed. While the rail is held by these clamps, the steam-cataract s may be actuated to cause the saw-slides $g g'$ to be moved along the supporting-frames $e e'$, thus causing the two saws $f f'$ to saw off the projecting ends of the rail in a well-known manner. The two sets of clamps may now be disengaged from the rail by reversing the steam-cataract s , whereupon the driven rollers a' will remove the rail from the saw-table and receive the next rail to be sawed.

Having thus described my invention, what I claim as new, and desire to secure by Letters Patent, is—

1. In a saw-table for a rail-mill, the combination with a saw adapted to saw off the ends of a rail lying upon said table, of a set of clamps adapted to engage with said rail as it lies upon the table and straighten the same in a given plane, a second set of clamps operating substantially at right angles to said first set, said second set of clamps being adapted to engage

said rail and straighten the same in a plane substantially at right angles to the plane of operation of said first set, whereby the rail may be straightened and the twist removed therefrom while being clamped for sawing, substantially as described.

2. In a saw-table for a rail-mill, the combination with saws adapted to saw off the ends of a rail lying upon said table, of a set of clamps 10 adapted to engage with said rail as it lies upon the table and straighten the same in a vertical plane, a second set of clamps adapted to engage said rail and straighten the same in a horizontal plane, said two sets of clamps thus 15 operating to remove twist from the rail, straighten the same and clamp it while being sawed, and means for removing the rail from the saw-table after being sawed, substantially as described.
- 20 3. In a rail-mill, the combination with a table for receiving a heated rail as it leaves the finishing-rolls, of a series of clamps which are arranged at intervals along said table and which have flat unyielding opposing members 25 for engaging corresponding flat surfaces upon said rail, and means for simultaneously actuating said clamps to straighten and remove twist from the rail, substantially as set forth.
4. In a rail-mill, the combination with a 30 saw-table for receiving a heated rail from the

finishing-rolls, of a saw for sawing off the end of the rail, clamps disposed at intervals along said table forming a row in the line of the rail and at an angle with the plane of the saw, flat unyielding faces on the opposing members of said clamps, means for actuating said clamps to cause the same to straighten and remove twist from the rail, and means for thereupon engaging the saw with the rail to saw off the end thereof, substantially as described. 35

5. The combination with a saw-table for receiving a heated rail from the finishing-rolls of a rail-mill, of a pair of saws for removing the ends of such heated rail, a series of clamps 40 arranged at intervals along the table between said saws, flat, unyielding engaging surfaces upon the opposing members of said clamps for engaging the top and bottom of the rail, means for simultaneously actuating said 45 clamps to straighten and remove twist from the rail, and means for engaging the saws with the heated rail to saw off the ends thereof, substantially as described. 50

In witness whereof I hereunto subscribe my 55 name this 18th day of November, A. D. 1897.

DAVID H. LENTZ.
